UNITED STATES PATENT OFFICE

2,432,254

BILFOLD WITH DETACHABLE FRONT
WALL POCKETS

Lester L. Sherwood, Los Angeles, Calif.

Application November 24, 1944, Serial No. 564,955

2 Claims. (Cl. 150—38)

1

My invention relates to improvements in billfolds and has for its principal object, to provide a simple, convenient and inexpensive billfold wherein the several parts which form the complete structure, are held in assembled relation by conventional snap fasteners, thus eliminating the time, labor and expense involved, where the parts, in manufacture, are united by stitching, adhesives, staples and the like.

A further object of my invention is, to provide a billfold composed of three main parts shaped, assembled and folded so as to provide a plurality of pockets open at their tops, for the reception of paper currency, checks and the like and other pockets open at both ends for the reception of cards, passes, identification certificates, drivers licenses and the like and which open ended pockets are normally closed by readily releasable flaps formed integral with the ends of certain of the wall forming members.

With the foregoing and other objects in view, my invention consists in certain novel features of construction and arrangement of parts which will be hereinafter more fully described and claimed and illustrated in the accompanying drawings in which:

Fig. 1 is an elevational view looking against the inner face of the billfold, the same being open or unfolded.

Fig. 2 is a horizontal section taken on the line 2—2 of Fig. 1.

Fig. 3 is a vertical cross section taken on the line 3—3 of Fig. 1.

Fig. 4 is a vertical cross section taken on the line 4—4 of Fig. 1.

Fig. 5 is a plan view of the member which forms the main body of the billfold.

Fig. 6 is a plan view of the pocket forming member which is located on the left hand portion of the body member.

Fig. 7 is a plan view of the pocket forming member which is located on the right hand portion of the body member.

Fig. 8 is a plan view of a partition forming member which is located between the main body and the open ended pocket forming members.

Referring by numerals to the accompanying drawings, which illustrate a preferred embodiment of my invention, 10 designates the outer wall of the billfold, which wall is rectangular in shape and integral with the upper edge of said outer wall is a substantially rectangular wall 11, foldable on dotted line *a* so as to overlie the front face of outer wall 10.

Integral with the ends of wall 10 are end flaps

12 and 13 foldable on the dotted lines *b*. And integral with the lower edge of said wall 10 between its center and ends, and foldable on the dotted lines *c*, are flaps 14 and 15. A small reinforcing flap 16 is formed on the lower edge of wall 10, between flaps 14 and 15 and when folded upward on the line *d*, reinforces the lower central portion of wall 10. (See Fig. 1.) Secured in the outer end portion of flap 12 is the socket member 12a of a conventional snap fastener and formed in flap 13 is an aperture 17 for the reception of the shank portion of the stud member of said fastener. Formed in flap 14 are apertures 18 for the reception of stud shanks and flap 15 is provided with a stud shank receiving aperture 19. Walls 10 and 11 and flaps 12, 13, 14 and 15 are formed from a simple piece of thin flexible material preferably leather. The pocket forming member which is mounted on the inner side of the left hand portion of wall 10, comprises a one piece L-shaped member 20 (see Fig. 6) foldable on the horizontal line *f* and vertical line *g* to form three walls 21, 22 and 23 approximately the same in size and shape.

25 Wall 21 is formed integral with one of the longitudinal edges of wall 22 and wall 23 is formed integral with one of the ends of said wall 22. Formed integral with the outer longitudinal edge of wall 21 near one end is a flap 24 foldable on dotted line *h* and said flap having a stud receiving aperture 25.

20 Formed integral with the free end of wall 23 is a flap 26 foldable on the dotted line *i* and seated in the outer portion thereof is the socket member 27 of a snap fastener.

30 Formed in wall 23 below and to one side of the center thereof is a stud receiving aperture 28 and similar apertures 29 are formed in wall 22 below and on opposite sides of the center thereof.

35 Socket 27, aperture 28 and apertures 29 are in longitudinal alignment with each other.

40 The pocket forming member which is mounted on the inner side of the right hand portion of wall 10, comprises a one piece L-shaped member 30 (see Fig. 7) foldable on the horizontal line *k* and vertical line *l* to form three rectangular walls 31, 32 and 33 approximately equal in size and shape.

45 Projecting from the free longitudinal edge of wall 31 is a small tab 34 foldable on line *j* and said tab has a stud receiving aperture 35. Formed integral with the free end of wall 33 is a flap 36, foldable on line *k* and seated in the outer portion of said flap is a socket 37. Formed in the lower central portions of walls 32 and 33, in lon-

3

gitudinal alignment with socket 37, are respectively, stud receiving apertures 38 and 39. Fig. 8 shows a plan view of a rectangular insert 40, which when the billfold is assembled for use is positioned between the rear walls 21 and 31 of the open ended pocket forming members 20 and 30.

The three main parts of my improved billfold, viz, the body member 10, 11 and flaps thereon, also the members 20 and 30 are all formed from thin, flexible material, preferably leather.

When the parts of the billfold are assembled, lining wall 11 is folded along line *a* so as to overlie the inner face of wall 10, thus forming a secret pocket, open at its bottom and at both ends, between said walls 10 and 11. With wall 22 disposed above the left hand portions of walls 10 and 11 and with wall 23 to the left of wall 22, wall 21 is now placed on the exposed face of the left hand portion of wall 11, with tab 24 extending downwardly and wall 23 extending to the left and after wall 23 has been folded on line *g*, over onto wall 22, the two walls 23 and 22 are folded downward on line *f* so that wall 23 is positioned between said walls 21 and 22, and thus a pocket open at its inner end, is formed between said last mentioned walls and with a pocket open at its outer end between wall 21 and the left hand portion of insert 40. Tab 24 is now folded on line *h* upward to overlie the outer face of wall 22 after which, flap 14 is folded on line *c* upward so as to overlie tab 24 and the lower portion of wall 22 and the shanks of snap fastener studs are now seated in the left hand one of the apertures 29 through aperture 25 in tab 24 and through the left hand one of the apertures 18 in flap 14. The shank of a stud 27 is also seated in the right hand one of the apertures 29 also the right hand one of the apertures 18 with the studs of said shanks projecting from the face of flap 14.

Flaps 12 and 27 are now folded over onto flap 14, with sockets 12a and 27 engaged on the studs, thus closing the ends of the pockets between walls 22 and 23 also between walls 21, 23 and the left hand end of insert 40.

Flap 12 also closes the left hand ends of the pockets between walls 10 and 11, also between walls 11 and 21 and between the left hand end of insert 40 and corresponding ends of walls 21 and 23.

When member 30 is applied to the body of the billfold, wall 31 is laid on the right hand portion of lining wall 11 with tab 34 extending downward with wall 23 disposed above the right hand end of walls 10 and 11 and wall 23 to the right of said wall 32 and after wall 33 is folded on line *i* over onto wall 32, the two last mentioned walls are folded downward on line *k* with wall 40 lying against wall 31 and tab 34 is now folded on line *j* upward onto wall 32.

Flap 15 is now folded on line *c* onto the lower portion of wall 32, after which flap 13 is folded on line *b* over onto the right hand end of folded member 30 and flap 15.

The shank of a stud is now seated in coinciding apertures 39, 33, 35, 19 and 17 thereby securing member 30 in folded condition, to the body of the billfold and flap 36 may now be folded on line *k* onto the left hand portion of said member

4

30 with socket 37 engaging the stud on the front face of flap 13.

Flap 36 closes the inner end of the pocket between walls 33 and 32 and flap 13 closes the outer ends of the secret pocket between walls 10 and 11 also the outer ends of the pockets between walls 11 and 40, between walls 40 and 31 and between 31 and 33.

Thus members 20 and 30 which when folded, provide a number of pockets are secured to the bilateral portions of the billfold body and combine therewith, to form a very compact and convenient stitchless receptacle and carrier for paper currency, checks, cards, passes and the like.

It will be understood that minor changes in the size, form and construction of the various parts of my improved billfold may be made and substituted for those herein shown and described without departing from the spirit of my invention, the scope of which is set forth in the appended claims.

I claim as my invention:

1. In a billfold, the combination with a one piece body comprising an outer wall, an inner wall depending from the upper edge of said outer wall, flaps on the ends of said outer wall and spaced flaps on the lower edge of said outer wall, of a one piece L-shaped flexible member secured to and overlying the left hand portion of said body member and foldable to form three walls of equal size and shape with the spaces between said walls open at both ends, the flap on the left hand end of said outer wall foldable to close the outer ends of said spaces, a flap on the right end of the inner one of said three walls for closing the inner ends of the spaces between said three walls and means for detachably securing the flap on the left hand end of said outer wall and the flap on the inner one of said three walls to one of the flaps on the lower edge of said outer wall.

2. In a billfold, the combination as set forth in claim 1 with a one piece L-shaped member secured to and overlying the right hand portion of said body member and foldable to form three walls of equal size and shape, with the spaces between said walls open at both ends, the flap on the right end of said outer wall foldable to close the outer ends of said last mentioned spaces, a flap on the end of the inner one of said last mentioned three walls for closing the inner ends of the spaces between said walls and means for detachably securing the flap on the right hand end of said outer wall and the flap on the inner wall of said last mentioned three walls to one of the flaps on the lower edge of said outer wall.

LESTER L. SHERWOOD.
